CLAIM

The ornamental design for a selection display for merchandising, as shown and described.

DESCRIPTION

FIG. 1 is a perspective view of a selection display for merchandising showing our new design;

FIG. 2 is a front elevational view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The broken line portions of FIGS. 1-7, show unclaimed subject matter only and form no part of the claimed design.
